United States Patent Office.

CHARLES BENJAMIN WILLOUGHBY, OF UHRICKSVILLE, OHIO, ASSIGNOR
TO HIMSELF AND W. A. BOVEY, OF THE SAME PLACE.

Letters Patent No. 79,290, dated June 23, 1868.

IMPROVED CARBURETTER.

The Schedule referred to in these Letters Patent and making part of the same.

TO ALL WHOM IT MAY CONCERN:

Be it known that I, CHARLES BENJAMIN WILLOUGHBY, of Uhricksburg, in the county of Tuscarawas, and State of Ohio, have invented a new and useful Apparatus for Manufacturing Gas; and I do hereby declare that the following is a full, clear, and exact description thereof, reference being had to the accompanying drawing, and making a part of this specification, in which—

Figure 1 is a horizontal section, taken in the line $x x$ of fig. 2, and

Figure 2 is a vertical section, taken in the line $y y$ of fig. 1.

The nature of my invention consists in the peculiar manner of generating gas from naphtha.

Its construction and operation are as follows:

In the drawing, A represents the pipe, which conveys the oil to the tank B in the bottom of the machine. On the top of the pipe A is a funnel, α , into which the oil is poured, and at the bottom of the funnel α is a stop-cock, b , which is kept closed except while the machine is being supplied with oil. The oil-pipe A discharges into the tank B, near the top, as seen in fig. 2.

C represents an air-pipe, (through which air is forced,) which extends down outside and under the machine, and thence upward into the oil-tank B.

In the drawing this pipe is represented as having two outlets.

At the inner ends of the pipe C are ball-valves, $c c$, which allow the air to pass into the oil, but when there is no pressure of air against the valves they remain closed, thus preventing any leakage of oil into the air-pipe or return of air. Above the oil-tank B is a gas-chamber, D, and between the oil-tank and the gas-chamber are ball-valves, $d d$, which allow the gas generated from the oil in the tank B to escape into the gas-chamber D.

In the top of the chamber D is an aperture, e , over which is placed a pipe, E, which extends to the side of the said chamber D, thence downward to the bottom of the water-tank F, where it branches off and extends around about half of the circumference of the tank B, and on the end of each branch-pipe is a ball-valve, f . A sufficient quantity of water is placed in the tank F to rise nearly to the top of the gas-chamber D, but does not come up as high as the top of the pipe E. Consequently, should water get into the said pipe, it could not rise high enough to flow into the chamber D.

Inside of the water-tank is placed the gasometer G, which operates in the usual manner. Inside of the gasometer is a pipe, H, the upper end of which extends up to the top of the water-tank, through which the gas passes to the burner.

Its operation is as follows: The oil is poured into the funnel α , and flows through the pipe A to the oil-tank B. When there is a sufficient quantity of oil in the tank, the stop-cock b is closed. Air is then forced into the oil through the pipe C. The gas is then generated from the oil, and passes through the valves $d d$ into the chamber D, thence through the pipe E into the water in the tank F, by which means it is washed and rises into the gasometer G, and by the pressure of the gasometer is forced into the pipe H, which supplies the burner. The oil being entirely surrounded by water, obviates all danger of explosion.

This apparatus also has the advantage of being so constructed that no smell of the oil escapes, thus overcoming one of the great objections to gas-machines.

Having thus fully described my invention, what I claim, and desire to secure by Letters Patent, is—

1. The combination of the oil-tank B, gas-chamber D, pipes and valves d , all as shown and described, and for the purpose specified.
2. The combination of the gas-chamber D, gas-pipe E, and valves f , substantially as shown and described, and for the purpose specified.
3. The combination of the oil-chamber B, the air-supply pipe C, and valve c , substantially as shown and described, and for the purpose set forth.
